AUTOMATIC SHUT-OFF DISPENSING NOZZLE VALVE WITH TIMER CONTROLLED SHUT-OFF

Edgar P. Turner, Watchung, N.J.

Application August 12, 1957, Serial No. 677,644

7 Claims. (Cl. 222—47)

This invention relates to automatically operated flow control valves or nozzles of the type exemplified by such patents as Payne, No. 1,550,738; Davis, No. 2,320,033; and Duerr, No. 2,582,195; and wherein approximate filling of a receptacle by way of such nozzle serves to automatically close the valve.

More particularly this invention relates to mechanism which enables a fluid dispensing nozzle valve to be automatically shut off at the end of a predetermined time while retaining the feature of automatic shut-off responsive to the filling of the receptacle.

A current problem arises in the dispensing of gasoline where the customer requests a certain amount or more specifically, a certain number of dollars worth of gasoline. With present equipment, it is necessary for the attendant to remain at the nozzle until the proper amount is indicated on the pump register so that he can then manually shut off the valve. This represents unproductive waiting time and unnecessary captive labor which is unavailable for servicing other customers who may even then be waiting somewhat impatiently at idle pumps.

According to the present invention means are incorporated in the dispensing nozzle itself whereby a setting can be made in accordance with the amount of gasoline requested, which setting establishes a time limit on the flow through the nozzle at the end of which time the valve is shut off automatically and the customer has received his requested amount of gasoline. In this case, the attendant need not stand by the nozzle waiting for the specified amount to be dispensed but is free to go about other work.

A primary object of this invention, therefore, is to provide a dispensing nozzle valve which may be preset to deliver a specified amount of fluid and then to shut off automatically when the specified amount has been delivered.

A further object of this invention is to provide a fluid dispensing nozzle valve having a dial calibrated in dollar units of delivered fluid and means for adjusting the flow through said nozzle to make the value of the amount of fluid delivered equal to the indicated dollar unit.

A still further object of this invention is to provide a dispensing nozzle valve in which a mechanically wound timer is set to shut off the valve after a predetermined time has elapsed.

Another object of this invention is to provide a timer-controlled dispensing nozzle valve in which the act of manually opening the valve starts the timer running.

The above and other objects and features of the invention will in part be obvious and will in part be apparent from the following detailed description and the drawing in which:

Figure 1 is a longitudinal section taken through an automatic shut-off nozzle valve constructed in accordance with an embodiment of this invention.

Figure 2 is a top plan view partly in section taken on the line 2—2 of Figure 1.

2

Figure 3 is a bottom plan view partly in section taken on the line 3—3 of Figure 1.

Figure 4 is a top plan view showing the timer dial of the valve of Figure 1.

5 Figure 5 is a longitudinal sectional view showing a modification of the structure of Figure 1.

Referring now to Figure 1 there is shown an automatic shut-off dispensing nozzle valve substantially the same as that shown in the United States Patent No. 2,582,195 except that it is modified according to the present invention to include means for automatically shutting off the valve at the end of an adjustable preset time interval. Reference may be had to the above mentioned patent for a more detailed description of the nozzle valve per se.

15 It will be sufficient for this description to note that the nozzle valve comprises a body 10 provided with an inlet passageway 11 which leads to a valve seat 12 on which a main valve 13 is normally pressed or seated by a spring 14. When the main valve 13 is open, inlet passageway 11 communicates with an outlet passageway 15 which in turn is connected to a discharge nozzle 16.

20 The main valve 13 is provided with a valve stem 17 disposed to be engaged at its lower end by a hand lever 18 when the lever is actuated upwardly to lift the valve off the seat 12 against the force of the spring 14. A fulcrum comprises a pin 19 on which the lever 18 is pivotally mounted. The pin 19 is supported by a yoke 20 connected to the lower end of a plunger 21 which is slidably disposed in a sleeve 22 integral with the valve body 10, and an externally threaded sleeve 23, the latter being threaded into sleeve 22. The plunger 21 is urged upwardly by a coil spring 24 but is restricted in its travel by contact of yoke 20 with the base of body 10. It is urged downward by spring 14 as will be explained.

25 Normally, the plunger 21 is held in a fixed position by a locking mechanism comprising a plurality of balls 25 nested in radial openings 26 in the plunger 21 and on annular shoulder 27 on the interior of sleeve 23. The balls 25 are held on shoulder 27 by a pin 28 secured to the underside of a spring-loaded diaphragm 29. The pin 28 is provided with a tapered portion 30 at a location slightly below the balls 25. Below tapered portion 30 the pin 28 includes a depending stem 31 which serves as a ball retainer. Thus, when the pin 28 is raised to a position

30 where the tapered portion 30 is adjacent the balls 25, plunger 21 will be actuated downwardly provided hand lever 18 is in its valve opening position. This movement of the plunger 21 results because of the stronger force of the spring 14 and the relatively weaker force of the spring 24. When the plunger 21 moves downward, yoke 20 is released to the dotted line position shown in Fig. 1 whereby the valve stem 17 is disengaged from hand lever 18.

35 A constricted throat or passageway 32 on the discharge side of the main valve 13 communicates by way of a duct 33 to a chamber 34 above the diaphragm 29 formed by a cap member 35 which is secured to the valve body 10 and clamps the marginal edge of the diaphragm 29. Located in the cap member 35 is a port 36 leading from the chamber 34 into a transverse cylindrical bore 37 in which slides a piston valve 38 to cover or uncover said port 36. Leading out of said bore 37 is a port 39 which connects with a tube 40 the open end 41 of which is at adjacent the outlet of the nozzle 16.

40 The cap member 35 is formed with a recess 42 in which is contained a spring-wound clock or timer mechanism 43 of conventional form. The timer 43 is secured to a plate 44 seated on an annular shoulder 45 formed in the cap member 35. The timer 43 is wound or set by rotating a knob 46 secured to the timer shaft 47. Index markings 48, preferably in dollars but which may also be

in gallons, are carried on a dial plate 49 secured to the timer shaft 47 and show through a transparent window 50 having a hair line 51 and fixed in a cover 52 secured to the cap member 35 as seen best in Fig. 4.

A first cam plate 53, seen best in Fig. 3, having a sloped notch 54 is driven by the timer. A second cam plate 55 having a sharper notch 56 is driven by said first cam plate 53 through a lost-motion pin and slot connection 57 as shown. The second cam plate 55 has a diameter slightly larger than the first cam plate 53 and bears against a follower pin 58 secured to a lever 59 pivoted at 60. A biasing spring 61 urges the lever 59 in a direction to keep the follower pin 58 in contact with the periphery of the second cam plate 55.

The lever 59 is formed with a down-turned terminal portion 62 which enters an aperture 63 in the transverse wall of the cap member 35 as seen best in Fig. 2, and is seated in a reduced portion 64 of the piston valve 38 so that the movement of lever 59 will cause movement of the valve 38. The arrangement of the parts is such that, when the pin 58 is at the bottom of the notch 54, the piston valve 38 closes the port 36 and the zero index 48 is on the hair line 51. By turning the knob 46 clockwise in Fig. 4 the cam plate 53 in Fig. 3 is turned counterclockwise and the follower pin 58 is cammed out of the sloped notch 54 and causes the lever 59 to rotate and move the piston valve 38 to uncover the port 36. The timer 43 then starts running and rotates the cam plate 53 in the direction shown by the arrow in Fig. 3. The second cam plate 55 is driven by the first cam plate 53 through the slot and pin connection 57 and after a predetermined time the follower pin 58 is suddenly pulled into the sharp notch 56 by the action of spring 61 thereby rotating the lever 59 and moving the piston valve 38 to cover the port 36. It will be seen that closing the port 36 is equivalent to closing the opening 41 by a full receptacle and results in upward movement of the diaphragm 29 and causes the main valve 13 to close as explained fully in the United States Patent No. 2,582,195.

Pivotedly secured to the valve body 10 is a swing latch member 65 adapted to engage and hold the hand lever 18 in the open position of the valve 13. A hair-pin spring 66 biases the latch 65 to the dotted line position so that it must be positively set. An adjusting screw 67 secured to the swing latch 65 permits the hand lever 18 to be positioned for various degrees of opening of the main valve 13 corresponding to various rates of flow through the nozzle. This adjustment is used for initial calibration and subsequently when a price change occurs in the fluid being dispensed, the flow rate can be readjusted by means of screw 67 until the dollar markings 48 on the dial 49 correspond to the dollar value of the fluid dispensed.

It will be understood that the addition of the timer and valve mechanism to the prior art dispensing nozzle valve does not in any way alter the existing advantages of the automatic shut-off responsive to a filled receptacle. In this case the timer is merely turned to its maximum index position which corresponds to a time greater than that necessary to fill the largest tank.

If desired, the rate set by the adjusting screw 67 can be made slightly less than that required to give full measure at the time of automatic shut-off, so that the attendant may thereafter complete the filling to the exact required amount by manual control of the nozzle valve.

To insure that the timer 43 begins timing responsive to the actuation of the hand lever 18 to open the main valve 13 as is desired, the slightly modified structure of Fig. 5 is used. In this case a pin 68 is slidably received in a sleeve 69 to which is secured the diaphragm 29 by means of a nut 70. The sleeve 69 is slidably received in the plunger 21 and the pin 68 seats against the bottom of a bore 71 in the plunger 21. A short pin 72 slidably in the cap member 35 bears at one end against the pin 68 and at the other end against a lever 73 pivoted

at 74 on the timer 43. The lever 73 is biased downwardly as shown by means of a spring 75 and carries at its opposite end a pin 76 which frictionally contacts an escapement wheel 77 of the timer 43 to prevent its running in the position of the parts as shown. It will be seen that, in this position, there is some vertical lost motion between the balls 25 and the radial openings 26 in the plunger 21 which is normally maintained by the spring 24 urging the plunger 21 upwardly against the combined downward thrust provided by the spring 75 and a diaphragm spring 78. However, when the hand lever 18 is pulled up to open the main valve 13, it initially pivots on the end of the stem 17 (Fig. 1) due to the spring 14 being stronger than spring 24, and the plunger 21 is pulled downward to take up the vertical lost motion between the balls 25 and the radial openings 26. This movement allows the pin 68, urged by the spring 75, to follow the plunger 21 and, in so doing, the lever 73 moves downwardly to disengage the pin 76 from the escapement wheel 77 and allow the timer 43 to start running. After the vertical lost motion is thus taken up, the balls 25 prevent further downward movement of the plunger 21 and the hand lever 18 pivots about the pin 19 and lifts the valve stem 17 and with it the valve 13 to start the flow through the nozzle. In this manner the timer 43 does not start timing out until the flow through the nozzle begins and accurate delivery in accordance with the settings of the dial 49 is thus obtained.

Having thus described the nature of the invention, what I claim herein is:

1. An automatic shut-off dispensing nozzle for fluids comprising a valve mechanism for controlling the flow of fluid through the nozzle, a diaphragm and a chamber associated therewith, said valve mechanism including a main valve having a passageway on the discharge side thereof constricted in the direction of flow therethrough, said constricted passageway and said chamber being in communication with one another, an orifice disposed adjacent the discharge end of the nozzle, a passage leading from said orifice to said chamber whereby air is drawn from said orifice through the diaphragm chamber into the constricted passageway when fluid flows therethrough and said orifice is exposed, valve means for closing said passage, timer means for closing said valve means at the expiration of a preset time whereby a pressure differential acts on said diaphragm to deflect same, and means responsive to said deflection to close said main valve to stop the flow of fluid through said nozzle.
2. A fluid dispensing nozzle comprising a main valve, a hand lever for opening said valve, a latch for holding said lever in the open position of said valve, a pivot for said hand lever movable to a position for releasing said lever to close the main valve, a diaphragm for moving said pivot to release position responsive to differential air pressure on opposite sides of said diaphragm, a control valve for establishing said differential pressure, and manually preset timer means for operating said control valve after a predetermined time interval to close said main valve automatically.
3. A fluid dispensing nozzle according to claim 2 in which the timer means carries a movable dial calibrated in dollars and a stationary index for setting the timer to shut off the main valve after an amount of fluid equal in value to the dollar setting has been dispensed through the nozzle valve.
4. A fluid dispensing nozzle according to claim 3 in which the latch for holding the hand lever in the open position of the main valve is adjustable to vary the rate of flow through the valve to compensate for changes in the unit price of the fluid so that the timer dial calibration in dollars is always correct.
5. A fluid dispensing nozzle according to claim 2 in which means normally operative to prevent the timer means from running is actuated responsive to manual movement of the hand lever to release the timer means

for running substantially coincidentally with the opening of the main valve.

6. A diaphragm operated, automatic shut-off liquid flow control nozzle comprising a diaphragm chamber, a diaphragm forming a movable wall of said chamber, a suction tube extending from the nozzle of the valve and normally communicating with the diaphragm chamber, a tube communicating at one end with said diaphragm chamber and having its other end exposed to a liquid flow through said valve, and a main valve controlling the flow of liquid therethrough, a cap member forming a rigid wall of said diaphragm chamber, a transverse bore formed in said cap member, a first port in said bore communicating with said chamber, a second port in said bore communicating with said suction tube, a piston seated in said bore and movable to cover and uncover said first port, manually preset timer means secured to said cap member, lever means operatively connected to said timer means and to said piston for moving said piston responsively to actuation of said timer means at the end of a preset time period to cover said first port thereby blocking the suction tube and creating a pressure differential on the diaphragm to operate same and means responsive to said

diaphragm operation to close the main valve to stop the flow of liquid through the nozzle.

7. A fluid dispensing nozzle comprising a main valve, a hand lever for opening said valve, a latch for holding said lever in the open position of said valve, a pivot for said hand lever movable to a position for releasing said lever to close the main valve, diaphragm means for moving said pivot to release position responsively to differential air pressure on opposite sides of said diaphragm, a control valve for establishing said differential pressure, a manually preset timer for operating said control valve after a predetermined running time period of said timer to close said main valve automatically, holding means normally biased to prevent the timer from running and means operative responsively to the initial manual movement of said hand lever to release said holding means and allow the timer to start its timing period substantially coincidentally with the opening of the main valve.
